UNITED STATES PATENT OFFICE.

HOWARD S. COREY, OF MUNHALL, PENNSYLVANIA.

VALVE.

Application filed March 8, 1924. Serial No. 697,815.

To all whom it may concern:

Be it known that I, HOWARD S. COREY, a citizen of the United States, and resident of Munhall, in the county of Allegheny and

5 State of Pennsylvania, have invented certain new and useful Improvements in Valves, of which the following is a specification.

This invention relates to valves, and while 10 not limited thereto relates more particularly to valves primarily adapted for use as reversing valves in regenerative furnaces and the like.

One object of the present invention is to 15 provide a valve of this type that will maintain substantially perfect sealing when seated.

Another object is to provide a valve which 20 may be mounted in the flues leading from the regenerative chambers so as to control flow through said flues and thus eliminate the necessity of using slide dampers.

A further object is to provide a reversing 25 valve which is composed of few parts, only one of which is movable, thereby reducing wear to a minimum.

A still further object is to provide a valve 30 composed of the novel combination, arrangement, and combination of parts hereinafter described and illustrated in the accompanying drawings.

In the drawings, Figure 1 is a top plan showing the regenerative chambers, stack and connecting flues of a standard form of 35 regenerative furnace.

Figure 2 is a sectional elevation on the line II—II of Figure 1.

Figure 3 is a sectional elevation on the line III—III of Figure 1.

40 Figure 4 is an enlarged sectional elevation through the valve and valve seat.

Referring more particularly to the drawings, the numerals 2 and 2^a designate the regenerative chambers of standard construction, which are connected by flues 3 and 4, 45 respectively, with the stack 5.

The flues 3 and 4 are each provided with the novel reversing valve of my invention, designated as a whole by the letter A.

50 The valve A is composed of upper and lower seat members 6 and 7 respectively, the lower seat member being provided with a passageway 7^a for the circulation of a cooling medium. The upper seat member 6 is arranged on a horizontal plane in a suitable

opening in the upper wall of the flues and is provided with an upstanding rim 8, forming an inlet conduit for the air passing to the regenerative chambers.

The seat members 6 and 7 are provided 60 with projections 9 and 10, respectively, at one point in their circumference, which form connecting lugs and are detachably secured together by bolts 11 or the like.

The lower seat member 7 projects downwardly from the upper seat member 6 on an angle of approximately 45 degrees and is mounted on a suitable inwardly projecting rim or shoulder 12 formed in the flue. 65

The seat members 6 and 7 are provided 70 with depressions 14 and 15, respectively, in their lugs 9 and 10, respectively, which cooperate to form a spherical socket.

A flap valve 16 is mounted to seat on either of the seat members 6 or 7, and comprises a disk body portion having a projecting ball connection 17 adapted to be mounted in the socket formed by depressions 14 and 15, so as to form a universal pivotal 75 connection.

The body portion of the valve 16 has both its upper and lower edge beveled as at 19 and 20, respectively, to form a tight seal with the beveled faces 21 and 22 of the seat members 6 and 7, respectively. 80

The ball and socket mounting for the valve 16 permits a universal movement of the valve and thus insures perfect seating thereof.

A suitable mushroom valve 23 is suspended 90 over the inlet conduit formed by the rim 8 on the upper seat 6, and is adapted to regulate the inflow of air through the inlet.

The mushroom valve 23 is suspended 95 from suitable chains 24 which pass around sheaves 25 on a shaft 26 mounted in a supporting frame 27 secured to an overhead beam 28 or the like. The chains 24 are provided with counterweights 29 to counterbalance the valve 23. The shaft 26 is provided with a sheave 30 which is connected by a chain 31 to a sheave 32 on a power shaft 33 mounted in a stand 34 and adapted to be rotated by a crank 35. The valve 23 is only raised and lowered occasionally to 100 regulate the inflow of air and the hand operation is, therefore, sufficient, although a suitable power means for moving the valve may be provided if desired. 105

The valve 16 is provided on its upper face 110

2
with a centrally arranged guide bracket 36^a having an upstanding curved guide arm 36^c which is curved upwardly and rearwardly toward the hinged or pivotal connection of 5 the valve.

A suitable lifting chain 36 has its one end connected to the center of the bracket 36^a, in line with the center of the valve. The chain 36 is trained upwardly through a centrally disposed opening 37 in the valve 23 and thence over a sheave 38 mounted on a shaft 39 in the frame 27, and has its other end secured to a hydraulic cylinder 40. A suitable coiled spring 41 is shown between 10 the two sections of the chain 36 for the purpose of smooth working, without jar or shock when operating the valve. The curved guide arm 36^c serves to maintain the lifting chain 36 centrally within the opening 37, thus permitting operation either of 15 the valves 23 or 16 without interference with the other.

In operation the flap valve 16 on one side of the stack will be raised to seal against 20 the seat 6 and the valve 16 on the other side of the stack will be lowered to seal against the seat 7 when it is desired to reverse the furnace, and due to the universal pivotal mounting of the valve 16 a perfect seal will 25 be made with either the upper or lower seats.

While I have illustrated my valve as applied to a regenerative furnace requiring regeneration of air only, it will be understood 30 that my valve may be applied equally as well to furnaces requiring the regeneration of both air and gas by the simple addition of another set of valves.

I claim—

40 1. A reversing valve for regenerative furnaces and the like comprising upper and lower seat members secured together at one point in their periphery, each of said seat members being provided with a depression 45 at the point of junction, which depressions co-operate to form a substantially spherical socket, and a flap valve adapted to be seated against either of said seat members and provided with a ball shaped extension, said ball 50 shaped extension being mounted in said socket formed by the depressions in said seats so as to form a universal pivotal mounting for said valve.

55 2. A reversing valve for regenerative furnaces and the like comprising upper and lower seat members secured together at one point in their periphery, each of said seat members being provided with a depression 60 at the point of junction, which depressions co-operate to form a substantially spherical socket, a flap valve adapted to be seated against either of said seat members and provided with a ball shaped extension, said ball 65 shaped extension being mounted in said socket formed by the depressions in

said seats so as to form a universal pivotal mounting for said valve, and means for operating said valve.

3. A reversing valve for regenerative furnaces and the like comprising upper and 70 lower seat members secured together at one point in their periphery, each of said seat members being provided with a depression at the point of junction, which depressions co-operate to form a substantially spherical 75 socket, a flap valve adapted to be seated against either of said seat members and provided with a ball shaped extension, said ball shaped extension being mounted in said socket formed by the depressions in said 80 seats so as to form a universal pivotal mounting for said valve, and means for operating said valve, said means including a chain lifting element, and means on said valve for guiding said chain. 85

4. A reversing valve for regenerative furnaces and the like comprising upper and lower seat members secured together at one point in their periphery, each of said seat members being provided with a depression 90 at the point of junction, which depressions co-operate to form a substantially spherical socket, a flap valve adapted to be seated against either of said seat members and provided with a ball shaped extension, said ball shaped extension being mounted in said 95 socket formed by the depressions in said seats so as to form a universal pivotal mounting for said valve, and means for operating said valve, said means including a power cylinder, a lifting chain secured to the center of said valve and to said cylinder, and a curved guide bracket secured to said valve and adapted to guide and maintain said chain in the center of the opening in said 100 upper valve seat.

5. A reversing valve for regenerative furnaces, comprising upper and lower seat members, the upper of said seat members being arranged on a substantially horizontal plane, the lower of said seat members being detachably secured to the upper seat member at one point in its circumference and extending downwardly therefrom at approximately 45 degrees, each of said seat members being provided with a depression at the point of junction which co-operate to form a substantially spherical socket, a flap valve adapted to be seated against either of said seat members, said valve being provided with a ball shaped extension which is mounted in said socket to form a universal pivotal mounting. 110

6. A reversing valve for regenerative furnaces comprising upper and lower seat members, the upper of said seat members being arranged on a substantially horizontal plane, the lower of said seat members being detachably secured to the upper seat member at one point in its circumference and extend- 120

ing downwardly therefrom at approximately 45 degrees, each of said seat members being provided with a depression at the point of junction which cooperate to form 5 a substantially spherical socket, a flap valve adapted to be seated against either of said seat members, said valve being provided with a ball shaped extension which is mounted in said socket to form a universal pivotal 10 mounting, and means for operating said valve, said means including a power cylinder, a lifting chain secured to the center of said valve and to said cylinder, and a curved guide bracket secured to said valve and 15 adapted to guide and maintain said chain in the center of the opening in said upper valve seat.

7. The combination with a regenerative furnace having the usual regenerative chambers for preheating the air used in supporting combustion in the furnace, a stack, and suitable passageways or flues communicating with said regenerating chambers and said stack, of a reversing valve in each of said 20 flues adapted to close the passage to the stack and open the passage to the atmosphere and vice versa as the furnace is reversed, said valve comprising upper and lower seat members, said upper seat member being arranged horizontally in the top 25 wall of said flue and being provided with an upstanding rim forming an air inlet, said lower seat member being detachably secured

to the upper seat member at one point in its circumference and extending downwardly on 35 an angle therefrom so as to close the passage to the stack when the valve is seated thereon, each of said seat members being provided with a depression at the point of junction, which depressions co-operate to 40 form a substantially spherical socket, a flap valve adapted to be seated against either of said seat members, said valve being provided with a ball shaped extension which is mounted in said socket to form a universal 45 pivotal mounting, means for operating said valve, said means including a lifting chain secured to the center of said valve, means for operating said chain, and means for guiding and maintaining said chain in the center 50 of the opening through said upper valve seat, and means for regulating the amount of air entering said air inlet.

8. A reversing valve for regenerative furnaces comprising upper and lower seat members at an angle to one another, a flap valve adapted to be seated against either of said members, and a ball and socket joint pivotally connecting the flap valve with said seat members and adapted to permit the valve to 55 be accurately seated on either of said seat members.

In testimony whereof, I have hereunto set my hand,

HOWARD S. COREY.
